UNITED STATES PATENT OFFICE.

DANIEL BOONE AND DANIEL SEVIER, OF MUSKOGEE, OKLAHOMA.

PLAYER PIANO.

Application filed July 3, 1920. Serial No. 393,824.

This invention relates to improvements in player piano mechanism and has for its object the provision of means controlled by the note sheet for regulating the tempo throughout the playing of each individual selection, the means operating to set the tempo initially and also to accelerate or retard the speed of playing from time to time as may be called for by the particular selection.

10 An important and more specific object is the provision of a tempo regulating device which acts upon the pneumatic governors which control the speed of the motor.

15 Another object is the provision of a control device of this character which will be comparatively simple and inexpensive in manufacture, which involves but a few parts, and which is capable of installation upon player pianos of different makes.

20 With the above and other objects and advantages in view the invention consists in the details of construction to be hereinafter more fully described and claimed and illustrated in the accompanying drawings, in which:

Figure 1 is an elevation of a portion of the interior mechanism of a player piano equipped with my device,

Figure 2 is a plan view of our attachment,

30 Figure 3 is an end elevation thereof,

Figure 4 is a vertical section through the control bellows,

Figure 5 is an enlarged detail section on the line 5—5 of Figure 4,

35 Figure 6 is a plan view of the control valve box,

Figure 7 is a vertical section therethrough on the line 7—7 of Figure 6,

Figure 8 is a cross sectional view on the

40 line 8—8 of Figure 6,

Figure 9 is a cross sectional view on the line 9—9 of Figure 6,

Figure 10 is a longitudinal horizontal section on the line 10—10 of Figure 8,

45 Figure 11 is a fragmentary plan view of the note sheet.

Referring more particularly to the drawings, the numeral 10 designates the key board of a player piano of a conventional

50 type, and 11 indicates the box or casing for the pneumatics which control and effect the operation of the keys and hammers. This mechanism is not shown as it forms no part of the present invention but it is of course

55 understood that the key operating mecha-

nism is controlled from the tracker bar 17 which is mounted within the spool box 15 and which is formed with the usual perforations with which register perforations in the note sheet. The winding spool 9 for 60 the note sheet is mounted in the spool box 15 and is driven by the usual motor designated broadly by the numeral 8. The spool upon which the note sheet is initially wound is not shown as it is well known that this spool is held within the spool box above the spool 9. The transmission from the motor to the spools of course includes the usual rewind mechanism for rewinding the note sheet from the spool 9 on to its carrying spool 65 subsequent to the playing of the selection.

The numeral 13 designates the bellows operated in the usual manner and connected by pipes 14 with the motor speed governors indicated broadly by the numeral 12, the latter being connected with the motor by a conduit 12^a. The specific construction of these governors is not shown though in many instances the governor mechanism consists of a valve slidably mounted within an air chest for controlling the degree of suction exerted on the motor and thus regulating the speed thereof. The action of the governors is regulated by a rod 39 which is ordinarily moved by means of a lever which is located generally in advance of the key board for convenient manipulation by the operator.

In carrying out the present invention such control lever is unnecessary, hence it is not illustrated. In effecting this control we provide a control valve consisting of a body 18 which may be constructed, and in actual practice must be constructed of several pieces fastened together by any preferred means. This valve body is provided internally with a chamber 42 into which leads a passage 43 with which is connected a tube 19 leading to the bellows 13 whereby to create suction within the chamber. Within the body are chambers 44 and 44^a leading into the chamber 42 and covered by diaphragms 45 and 45^a. These valve chambers 44 communicate with the suction chamber 42 through passages 46 and 46^a and leading into these chambers 44 and 44^a are small passages 47 and 47^a from which extend tubes 20 and 20^a in which lead to auxiliary holes 21 and 21^a in the ends of the tracker bar, these holes being located outwardly of the perforations provided for controlling the action of the 110

pneumatics which effect playing of the piano. The valve body 18 is formed with small chambers 48 and 48^a which are located at the side of the chamber 42 opposite from that side where the chambers 44 and 44^a are located and these chambers 48 and 48^a communicate with the atmosphere through ports 49 and 49^a. Internally the body 18 is provided with holes 50 and 50^a which lead from the chamber 42 to the respective chambers 48 and 48^a at the centers of the latter. The body is also formed with passages 51 and 51^a which communicate with the holes 50 and 50^a respectively and from which lead tubes 25 and 25^a which are connected with the bellows structure to be described.

Slidable loosely through the holes 50 and 50^a are valve stems 52 and 52^a which have their ends engaging the diaphragms 45 and 45^a respectively. On these stems are valve disks 53 and 53^a and 54 and 54^a which are spaced as shown. This type of valve detail is well known in player piano construction.

Mounted on the box 11 is a double bellows 22 carried by suitable brackets 23. Both sides or members of the double bellows are connected by side bars 24 so that both sides must move simultaneously regardless of which is exhausted. The movement of the bellows is limited by adjustable stops 26. In detail, the bellows structure consists of a central partition 55 upon opposite sides of which are located hingedly mounted leaves 56 to which the side bars 24 are connected. The bellows further includes the usual flexible covering 57. By the specific structure illustrated it will be seen that there are thus provided two bellows members 58 and 58^a. The partition 55 is formed with passages 59 and 59^a communicating respectively with the bellows members 58 and 58^a and the tubes 25 and 25^a lead into these passages 59 and 59^a respectively.

Connected with the leaf 56 of the double bellows is one end of a bar 27 which extends along the entire player mechanism and which is slidable through a suitable guide 60 on the base of the spool box. The other end of this rod 27 is downturned as shown at 37 and is formed with a horizontal arm 38 located beneath the key board and terminating in an upward extension connected at 40 with the rod 39 of the motor speed control governor mechanism. Carried by the rod 27 is a pointer 35 which is movable over a fixed scale 36 mounted at the lower portion of the spool box at the customary location.

The note sheet 61 is formed at its opposite edges with perforations 41 and 41^a which register with the openings 21 and 21^a respectively in the tracker bar 17. These openings at each side are arranged in alternation, when they are provided at both sides

and it will be observed that the openings are arranged in groups or series, the length of the series, or the number of holes in each group depending upon the tempo of the selection to be played.

It is to be noted that the holes in the note sheet for governing the initial setting of the tempo are located at the very end of the note sheet, i. e. in advance of the perforations 62 which control the operation of the pneumatics for effecting playing.

The operation is as follows:

When the player piano is in operation and the note sheet is being drawn over the tracker bar, it is well known that there is suction through all of the perforations in the tracker bar. Owing to the fact that the control valve device is connected with the bellows through the tube 19, it will be apparent that there will be suction in the chamber 42 and owing to the provision of the passages 46 and 46^a, there will also be suction in the chambers 44 and 44^a, passages 47 and 47^a, and tubes 20 and 20^a which lead to the holes 21 and 21^a in the tracker bar.

Assuming that there are no holes 41 or 41^a registering with the holes 21 and 21^a, the holes 21 and 21^a are of course closed or covered by the note sheet and the suction through the pipe 19, chamber 42 and passages 46 and 46^a will exhaust the chambers 44 and 44^a so that the diaphragms 45 and 45^a will be concaved thereinto, the valves being in the position shown in Figures 8, 9 and 10.

As there is suction within the chamber 42 atmospheric pressure through the passages 49 and 49^a and within the chambers 48 and 48^a will hold the valves in the position shown, the disks 53 and 53^a seating against the inner walls of the chambers 48 and 48^a and the disks 54 and 54^a being spaced away from the wall of the chamber 42.

The chamber 42 is then in communication with the passages 51 and 51^a through the holes 50 and 50^a and suction is present through the tubes 25 and 25^a and consequently in both sides or chambers 58 and 58^a of the double bellows. The bellows will then remain in its neutral or intermediate position and the rod 27 will be in such position that the pointer 35 will be at the center of the scale 36 and the rod 39 in such position that the governors will regulate the speed of the motor to its intermediate degree.

Assuming that a series of holes 41 passes over the hole 21 in the tracker bar, the suction in the chamber 44 will be relieved as air enters through the tube 20 leading from the hole 21 in the tracker bar. The diaphragm 45 will then flatten out and the valve will be shifted from the position shown in Figure 8 to its other position with the disk 54 closing the hole 50 and the disk 53 uncovering the hole 50. The hole 50 then communicates with the chamber 48 which communicates to

the atmosphere to the passage 49 and the bellows member 58 will expand as atmospheric air will enter it. As this section of the bellows expands, the other section 58^a contracts owing to the provision of the wide bars 24. The result is that the rod 27 will shift to the left, causing corresponding movement of the rod 39 connected therewith and operation of the governors 12 to accelerate the speed of the motor. If it be that a series of holes 41^a should register with the hole 21^a, corresponding action of the other valve will occur which will permit the bellows section 58^a to expand and the section 58 to collapse so that the rod 26 will be moved in the other direction and the governors operated to decrease the speed of the motor which drives the spool. When it is intended that the tempo be intermediate, both edges of the sheet are provided with the perforations as indicated at the lower end of Figure 11. In actual practice the sheet is formed at its edges with groups or series of perforations arranged for example as illustrated in Figure 11, so that the two bellows members will alternately expand and contract and control of the speed of the motor in accordance with the proper tempo for the individual selection. The solid line at the center of Figure 11 will give an indication as to the changes in speed according to the arrangement of the holes 41 and 41^a. It should also be mentioned that as the automatic control is operated the pointer 35 moves over the scale 36 so that the performer or operator may know at a glance the tempo at which the selection is being played. In case the perforations are at both edges of the sheet so that the intermediate tempo can be maintained, the perforations are arranged in alternation as shown.

From the foregoing description and a study of the drawings it will be apparent that we have thus provided a simply constructed and easily installed automatic tempo control device which is adapted for use in connection with player pianos of different makes or types and which is of such construction that the individual selection will be played automatically in strict accordance with the proper tempo instead of the matter being left to the judgment of a per-

haps unskilled operator. The quality of the playing is thus bound to be improved. 55

While we have shown and described the preferred embodiment of the invention it is of course to be understood that we reserve the right to make such changes in the form, construction and arrangement of parts as 60 will not depart from the spirit of the invention or the scope of the subjoined claim.

Having thus described our invention we claim:

In a mechanical player piano, the combination with the motor and its speed governor, of a rod connected with the governor, a double bellows connected with said rod, a control valve device including two valves controlling passage of air through the respective members of the double bellows, and means for controlling said valves from a tracker by means of a perforated note sheet, said control valve device comprising a body formed with a large chamber having a tube 70 connection with the bellows of the player, said body being formed with pairs of small chambers located at opposite sides of the large chamber, diaphragms covering one pair of small chambers, the body being 75 formed with passages leading into the diaphragm covered chambers and connected with holes at the ends of the tracker, the body being further formed with passages establishing communication between the diaphragm covered chambers and the large chamber and being formed with other passages establishing communication between the other pair of small chambers and the atmosphere, 80 the body being formed with holes establishing communication between said last named pair of chambers and the large chamber and formed with passages communicating with said holes and having tube communication 85 with the respective sections of the double bellows, and a pair of valve members including stems slidable through said holes and bearing against said diaphragms, and further including pairs of disks for selectively cutting off communication between 90 the large chamber and the holes or the last named small chambers and the holes.

In testimony whereof we affix our signatures.

DANIEL BOONE.

DANIEL SEVIER.
